SHUTTLE MECHANISM FOR WEAVING MACHINES

Application filed July 25, 1930. Serial No. 470,712.

Our invention relates to improvements in shuttle mechanisms for weaving machines and the object of our invention is to devise a means for completely withdrawing the remnant thread from the shuttle when the exhausted quill or bobbin in the shuttle is expelled therefrom during the weaving operation.

A further object of our invention is to make our device of a simple and inexpensive nature so that it can be applied to any standard automatic loom without alteration or loss of time.

Our invention consists of a device of the foregoing nature constructed and arranged all as hereinafter more particularly described and illustrated in the accompanying drawings in which,

Fig. 1 is a perspective view of a standard shuttle as is used in weaving looms.

Fig. 2 is a front elevational view of a fragmentary portion of the discharge end of a loom shuttle race, and

Fig. 3 is an end elevational view of the portion illustrated in Fig. 2.

Like characters of reference indicate corresponding parts in the different views.

It will be understood by those conversant with the art of weaving that in automatic looms or any weft replenishing looms that the quill or bobbin upon which the weft thread is wound is when exhausted expelled from the shuttle and replaced by a new quill or bobbin whilst the loom is in continuous operation. Heretofore many thousands of dollars worth of lengths of material have been spoiled or reduced from first grade to second grade material through the remnant thread upon the exhausted and expelled bobbin remaining in the shuttle after the bobbin or quill has been expelled and the new bobbin or quill inserted, thus causing a double thread to be woven into the fabric during the following travel of the shuttle.

The standard quills or bobbins as illustrated in the drawings consist of a thread receiving shank 1 formed at one end with a head 2 by means of which the quill or bobbin is spring held in the shuttle 3.

The head of the quill or bobbin is necessari-

ly at the opposite end of the shuttle to the shuttle eye 4 as the head is gripped in the shuttle and the thread carried from the shank through the shuttle eye. When an exhausted quill or bobbin in the shuttle is being replaced, a replacement quill or bobbin is automatically positioned over the shuttle race at the discharge end of its stroke and when the shuttle pauses underneath the replacement quill, such replacement quill is forced downwardly by a plunger member 5 and enters the shuttle expelling the exhausted quill or bobbin which falls downwardly through a chute 6 into any suitable receptacle underneath.

As the head of the quill or bobbin is much heavier than the opposite end, it being of much greater diameter, and also as it is usually wound with metal bands 7, it will be readily perceived that the quill or bobbin in falling will swing so that the head 2 falls foremost. It will also be apparent that when the replacement quill or bobbin is forced downwardly expelling the exhausted quill or bobbin that the head of the replacement quill will strike the head of the exhausted quill, rather than the thread wound shank of the replacement quill striking the shank of the exhausted quill, so that the head of the exhausted quill is given this additional impetus in its downward and foremost swing.

It will be therefore apparent that when the quill or bobbin is expelled in the ordinary fashion that the heavy head portion will swing downwardly in the falling movement, thus permitting the remnant thread remaining upon the shank to wind itself thereoff as the quill or bobbin falls, thus leaving the end 8 of the thread in the eye 4 of the shuttle, so that such remnant thread remains in the shuttle and is carried across through the warp threads by the next shuttle movement which causes a double thread to be woven in as the thread upon the replacement bobbin is of course also woven into the fabric at the same time in the normal manner. As the thread is wound upon the shank of the quill or bobbin with the particular object of permitting it to readily unwind thereoff in passing to the eye, it will be readily apparent that the downward movement of the quill or bob-

bin in falling head first will readily permit the remnant thread upon the exhausted quill to remove itself therefrom and remain in the shuttle eye as the quill is falling.

- 6 In our present invention we change the direction of fall of the expelled quill or bobbin so that in its fall the head 2 is momentarily retarded in its downward movement or in fact bounced upwardly to a slight degree, so 70
10 that the shank 1 swings downwardly and falls foremost thus completely drawing the remnant thread 8 from out of the eye 4. To attain this end we secure a buffer member 9 in the downward path of travel of the head 15 2 and with which the head 2 comes into contact. In the construction as illustrated in the drawings the buffer member 9 is a metal L shaped member suitably secured to the side plate 10 of the chute 6. The head 2 of the 20 exhausted quill or bobbin as illustrated in Fig. 2 by the upper arrow falls foremost due to its weight and also due to the impact of the head of the replacement quill, until it comes into contact with the buffer 9 which 25 momentarily retards the head 2 in its downward movement thus permitting the shank 1 to swing downwardly into a foremost position as illustrated by the lower arrow in Fig. 30 2. The downward swing of the shank 1 prevents the remnant thread 8 from unwinding thereoff and draws such remnant thread from out of the eye 4 of the shuttle. The quill or bobbin then continues its fall downwardly into the receiving receptacle underneath.
- 35 In the carrying out of our invention in the provision of our buffer 9 we found that the resilient quality and position of such buffer were very important features. We found that if a substantially solid buffer were used 40 and positioned approximately as shown in our drawings that the head of the bobbin upon striking the buffer would occasionally bounce upwardly back into contact with the shuttle and jamb the mechanism, and that if 45 the buffer were placed further down the chute 6 so that the rebound of the bobbin head did not effect the shuttle, that very frequently the bobbin head in its downwardly swinging and falling movement would fall 50 clear of and not impact with the buffer. If in order to remedy this the buffer was extended out, however, into the path of fall of the bobbin, the bobbin would very frequently strike the buffer too close to the centre of 55 the bobbin shank and thus defeat the object of the invention in having the shank fall foremost.

It was therefore found that the practical solution to the various problems presented 60 was to have the buffer positioned adjacent to the shuttle substantially as illustrated in the drawings and to design the buffer of resilient or snubbing form, wherein, it had a resilient movement downwardly when struck 65 by the bobbin head so that any impact bounce

of the bobbin head was eliminated or very materially reduced or snubbed.

We have placed our device upon a number of looms which are in continuous use and have found that without exception the provision thereof entirely prevents the residue thread from remaining in the shuttle when the quills or bobbins are being replaced, and although we have described and illustrated a particular embodiment of our invention it 75 is to be understood that we may make such changes and alterations as we may from time to time deem necessary without departing from the spirit of our invention as set forth in the appended claims. 80

What we claim as our invention is:

1. In a loom, the combination with the shuttle and the expellable weft bobbin carried in the shuttle, of a substantially horizontal member projecting into the path of fall 85 of the expelled bobbin and with which the heavier end of the bobbin makes momentary contact.

2. In a loom, the combination with the shuttle and the expellable weft bobbin carried in the shuttle, of a resilient member projecting into the path of fall of the expelled bobbin and with which the heavier end of the bobbin makes momentary contact. 90

3. In a loom comprising a shuttle, an expellable bobbin carried in the shuttle, and a downwardly extending chute through which the expelled bobbin falls, of means positioned in the chute adjacent to the shuttle from which the bobbin is expelled and upon which the heavier end of the expelled bobbin momentarily rests. 100

4. In a loom, the combination with the shuttle and an expellable weft bobbin carried in the shuttle, of a buffer member projecting into the path of fall of the expelled bobbin and upon which the heavier end of the bobbin momentarily rests. 105

5. In a loom comprising a shuttle, an expellable bobbin carried in the shuttle, of a buffer member positioned in the path of the expelled bobbin adjacent to the shuttle from which the bobbin is expelled and upon which the heavier end of the expelled bobbin momentarily rests. 110
